US00D499723S

(12) **United States Design Patent** (10) Patent No.: **US D499,723 S**
 Kagami et al. (45) Date of Patent: **** Dec. 14, 2004**

(54) **PORTION OF A HANDSET**

(75) Inventors: **Junichi Kagami**, Tokyo (JP); **Robert Shepherd**, Tarzana, CA (US); **Todd Wood**, Santa Monica, CA (US); **Paresh Desai**, Marina del Rey, CA (US)

(73) Assignee: **Nokia Corporation**, Espoo (FI)

(**) Term: **14 Years**

(21) Appl. No.: **29/183,521**

(22) Filed: **Jun. 13, 2003**

(51) LOC (7) Cl. **14-03**

(52) U.S. Cl. **D14/248**

(58) Field of Search D14/137, 138, D14/218, 147-148, 247-248, 144, 341-347; 379/433.01-433.13, 419, 434, 428.01-428.04, 420.01-420.04, 440; D10/65, 78; 455/550.1-90.3; D21/517; D13/168; D18/2, 7; 345/168, 169
